ELECTRICAL PLUG DEVICE

Emanuel P. Clark, Jr., South Norwalk, Conn.

Application February 7, 1931. Serial No. 514,159

8 Claims. (Cl. 173—334)

The present invention relates to improvements in electrical plug devices, and has for an object to provide in such a device a novel plug and resilient contact unit formed of one piece of material, and which will be of inexpensive and reliable construction. It is a further object to provide such a unit having a plugging portion or blade of substantially rigid construction formed by bending the material upon itself to form a double thickness reinforced structure, and to provide as an integral continuation thereof a resilient contact portion in combination with lead wire attaching means and means for positioning and retaining the unit in a suitable insulating block.

With the above and other objects in view, embodiments of the invention are shown in the accompanying drawings and these embodiments will be hereinafter more fully described with reference thereto and the invention will be finally pointed out in the claims.

In the drawings:

Fig. 1 is a front elevation of an electrical plug device, embodying the invention.
 25 Fig. 2 is a side elevation thereof.
 Fig. 3 is a top plan view.
 Fig. 4 is a top plan view of the block employed, with parts removed.
 Fig. 5 is a vertical sectional view of the device 30 taken along the line 5—5 of Fig. 3.
 Fig. 6 is a vertical sectional view taken along the line 6—6 of Fig. 3.
 Fig. 7 is a perspective view of the plug and 35 resilient contact unit, according to the invention.
 Fig. 8 is a front elevation showing a modified form of the invention.
 Fig. 9 is a side elevation thereof.
 Fig. 10 is a top plan view.
 Fig. 11 is a vertical sectional view along the line 40 11—11 of Fig. 9.

Fig. 12 is a perspective view of the modified plug and resilient contact unit employed.
 Fig. 13 is a vertical sectional view, similar to Fig. 11, and showing another modified form of 45 plug and resilient contact unit.

Fig. 14 is a perspective view of the plug and resilient contact unit shown in Fig. 13.
 Fig. 15 is a vertical sectional view showing a further modification.
 50 Fig. 16 is a perspective view of the modified plug and resilient contact unit shown in Fig. 15.

Similar reference characters indicate corresponding parts throughout the several figures of 55 the drawings.

Referring to the drawings, and more particu-

larly to Figs. 1 to 7 thereof, the embodiment of the invention shown therein comprises a pair of identical plug and resilient contact devices or units, presently to be more fully described, and which are arranged in an insulating block 20 formed of hard rubber, "Bakelite" or other suitable material. A central lead wire passage 21 communicates at its lower end with a transverse passage 22 and at its upper end with a widened rectangular lead wire receiving space 23, surrounded by an upstanding wall portion 24 of the block. At each side of the central lead wire passage 21 there is provided a pocket 25 of rectangular form having vertical side walls, and a passage 26 extending from the pocket to the base 70 of the block, the inner wall of this passage being flush with the inner wall of the pocket. A downwardly extending recess 27 is formed in continuation of the outer wall of the pocket. The inner wall of the pocket projects upwardly, as at 75 28, into the widening lead wire receiving space 23.

The plug and resilient contact devices or units, according to my invention, are blanked from a single piece or strip of suitable metal, bent upon itself, as at 29, to form a double thickness substantially rigid plugging portion 30, the outer leg of which is bent outwardly as at 31, and downwardly as at 32, so that it may be forced into the socket 25 of the plug with the inner leg engaging the inner wall of the socket, the downwardly bent portion 32 engaging the outer wall with its lower end forced into the recess 27, and the outwardly bent portion 31 substantially flush with the base of the space 23. At a point below the bend of the portion 31 the inner leg is provided with an offset bend 33, and a single thickness resilient contact portion 34 extends below this bend into the passage 26 in spaced relation to the inner wall of the socket, being diagonally bent at its lower end, as at 35 to provide a guide surface for facilitating entry of a plug.

The upper end of the plugging portion 30 is preferably beveled at the corners, as at 36, and with the rounded end formed by the bend 29 provides an easy entering structure. A contact engaging aperture 37 is punched in the portion 30 at a suitable point, and the resilient contact portion 34 is provided with a pressed out contact boss 38.

The portion 31 is provided with a tapped hole engaged by a screw 39 which serves as a binding post for securing the end of a lead wire to the unit, the lead wire extending in the space 23 at the side of the wall portion 28 and downwardly through the passage 21 from which it may be ex-

tended laterally through the passage 22. If desired the screws 39 may be removed and the end of the lead wire secured by soldering to the portion 31.

5 The plugging portions 30 of the two units are snugly engaged in slots 40 of a cover plate or washer 41 of insulating material snugly fitted within the wall 24 of the block to close the space 23.

10 It will be observed that the support of the unit in the insulating block is such that the integral structure, comprising the rigid plugging portion 30, the lead wire attaching portion 31, the extension portion 32, and the inner leg of the plugging 15 portion above the offset bend 33, is firmly held in place against displacement or distortion and forms a firm support for the integral resilient contact portion 34, enabling the latter to flex during engagement and disengagement of a plug 20 therewith, without strain and without the objections to breakage, loosening, separation, or displacement of the parts present in devices heretofore in use.

25 In Figs. 8 to 12 I have shown a modified form of the invention in which the insulation block comprises two half sections 42, divided in a vertical plane, and secured together by a transverse bolt 43. The inner faces of the half sections have recesses and channels therein, which upon joining the sections together form pockets and passages for receiving and retaining the plug and resilient contact units and the lead wires.

30 As clearly shown in Fig. 11, a vertical recess 44 is provided at each side of the center having a shoulder 45 upon the outer wall near its upper end and opening at its inner wall, as at 46, into a lead wire receiving space 47 from which a transverse aperture 48 extends to the exterior. The recess 44 above the shoulder 45 is widened 35 outwardly and near its inner wall is provided with a plug receiving recess 49 extending through the upper end of the block. A transversely extending cylindrical recess 50 is provided in the inner wall in line with the widened upper end of the recess 44. The recess 44 is open at its lower end and is provided with a rib 51 for guiding a plug therein, and in spaced relation to the lower end there is provided a rib 52. In the assembled relation of the two sections the passages formed 40 between the recesses 49 and between the ribs 51 are of a width to receive the plug and resilient contact units, while the passages formed by the recess 44 are wider to provide spaces at the sides of the units for the lead wires.

45 The plug and resilient contact unit comprises a plug portion 53 similar to that disclosed in the first embodiment, and formed of a strip of metal bent upon itself. The outer leg terminates at a point in line with the shoulder 45 while the inner leg is extended downwardly to form a resilient contact portion 54, being diagonally bent at its lower end, as at 55, to provide a plug guiding surface. At a point in line with the recess 50 the legs are provided with a tapped aperture 56 engaged by a screw 57 the head of which is positioned in the upper widened portion of the recess 44, while the shank engages the recess 50, thus positioning the unit against longitudinal displacement and providing a binding post for attaching a lead wire.

50 In the modification shown in Figs. 13 and 14 the outer leg of the plug and resilient contact unit is bent outwardly, as at 58, to engage in the widened upper end of the recess 44, and is adapted to position the unit against longitudinal

displacement and provide means to which the end of the lead wire may be fastened by solder. The inner leg in this embodiment is provided with an offset bend 59 adjacent the end of the outer leg, the latter being bent outwardly below the shoulder 45, as at 60.

80

55 In Figs. 15 and 16 I have shown a further modification in which the insulating block member 61 employed is somewhat similar to that shown in the first embodiment, but of a design to accommodate a modified form of plug and resilient contact unit, according to my invention. The plug portion 62 of the unit is similar to that disclosed in the other embodiments being formed by bending a strip of metal upon itself. The outer leg is bent outwardly as at 63, and then inwardly upon itself as at 64, beneath the extremity of the inner leg, being carried beyond the inner leg for a short distance to provide a surface for attaching a lead wire by soldering, and is then bent downwardly, as at 65, and upwardly as at 66, at an inclined angle, this latter portion constituting the resilient contact part of the unit.

85

60 The plug portion 62 is engaged in a slot 67 in a cover plate or washer 68 seated in the recess 69 at the upper end of the block and secured by a screw 70 to the central partition portion 71. The lateral extension formed by the portions 63 and 64 is seated in a shouldered recess 71 at the upper end of the plug receiving pocket 72, provided at each side of the partition portion 71, being retained therein by the cover plate 18. The pocket 72 has a vertical inner wall and an inclined outer wall, and is provided at its lower end with a plug receiving slot 73, through which a plug may be inserted to engage the resilient contact portion 66 of the unit. The lead wire, which as above pointed out is soldered to the portion 64, is carried through an opening 74, provided in each side wall of the pocket 72, and which opens into a space 75, at each side of the block, and from which the wire is carried to the exterior through a passage 76 provided in the outer wall of the block, at each side.

90

95

65 I have illustrated and described preferred and satisfactory embodiments of the invention, but it will be obvious that changes may be made therein, within the spirit and scope thereof, as defined in the appended claims.

105

70 Having thus described my invention what I claim and desire to secure by Letters Patent is:—

110

75 1. In an electrical circuit extension plug device, a housing of insulating material having a plug blade receiving socket, and a metallic plug and resilient contact unit carried in said housing, comprising a single strip of metal bent upon itself for a portion of its length to form a double thickness relatively stiff plug portion adapted to project from said housing and an integral single thickness relatively flexible extension forming a resilient contact portion, said contact portion being disposed in said plug blade receiving socket to form a plug engaging contact.

115

80 2. In an electrical circuit extension plug device, a housing of insulating material having a plug blade receiving socket at one end, and a metallic plug and resilient contact unit carried in said housing comprising a single strip of metal bent upon itself for a portion of its length to form a double thickness relatively stiff plug portion adapted to project from the end of said housing opposed to said socket end and an integral single thickness relatively flexible extension longitudinally aligned with said plug portion

120

125

130

135

140

145

150

- and forming a resilient contact portion, said contact portion being disposed in said plug receiving socket to form a plug blade engaging contact. 3. In an electrical circuit extension plug device, a housing of insulating material having a plug blade receiving socket and a plug unit positioning cavity, and a metallic plug and resilient contact unit carried in said housing comprising a single strip of metal bent upon itself for a portion of its length to form a double thickness plug portion to project from said housing, a laterally offset portion for engaging said positioning cavity of the housing and an integral single thickness extension longitudinally aligned with said plug portion and forming a resilient contact portion, said contact portion extending into said plug blade receiving socket to form a plug engaging contact. 4. In an electrical circuit extension plug device, a housing of insulating material having a plug blade receiving socket and a longitudinally extending plug unit positioning cavity, and a metallic plug and resilient contact unit carried in said housing comprising a single strip of metal bent upon itself for a portion of its length to form a double thickness plug portion to project from said housing, a longitudinally extending laterally offset portion for longitudinally engaging in said positioning cavity of the housing, and an integral single thickness extension forming a resilient contact portion, said contact portion extending into said plug blade receiving socket to form a plug engaging contact. 5. An electrical circuit extension plug device, comprising a housing of insulating material having a pair of spaced plug blade receiving sockets, and a pair of metallic plug and resilient contact units carried in spaced relation in said housing, each comprising a single strip of metal bent upon itself for a portion of its length to form a double thickness relatively stiff plug portion adapted to project from said housing in correspondingly spaced relation to the spacing of said sockets and an integral single thickness relatively flexible extension forming a resilient contact portion, said contact portions being respectively disposed in said plug receiving sockets to form plug engaging contacts, adapted to be engaged by the plug portions of a similar plug device. 6. In a plug receiving socket, a metallic plug and resilient contact unit, comprising a single strip of metal bent upon itself for a portion of its length to form a double thickness relatively stiff plug portion and an integral single thickness relatively flexible extension forming a resilient contact portion adapted to be engaged by a plug inserted in said plug receiving socket. 7. In a plug receiving socket, a metallic plug and resilient contact unit, comprising a single strip of metal bent upon itself for a portion of its length to form a double thickness relatively stiff, plug portion and an integral single thickness relatively flexible extension longitudinally aligned with said plug portion and forming a resilient contact portion adapted to be engaged by a plug inserted in said plug receiving socket. 8. In a plug receiving socket, a metallic plug and resilient contact unit, comprising a single strip of metal bent upon itself for a portion of its length to form a double thickness relatively stiff plug portion, a lead wire attaching portion, and an integral single thickness relatively flexible extension forming a resilient contact portion adapted to be engaged by a plug inserted in said plug receiving socket.
